UNITED STATES PATENT OFFICE.

ALBERT BRUNO SCHAEFER, OF NEW YORK, N. Y.

HEEL FOR SHOES.

1,341,521.

Specification of Letters Patent. Patented May 25, 1920.

Application filed August 5, 1919. Serial No. 315,469.

To all whom it may concern:

Be it known that I, ALBERT BRUNO SCHAEFER, a citizen of the United States, and a resident of the city of New York, 5 borough of Manhattan, in the county and State of New York, have invented a new and Improved Heel for Shoes, of which the following is a full, clear, and exact description.

0 The present invention relates to new and useful improvements in heels for shoes, and it pertains more particularly to heels of the resilient type.

5 The primary object of the invention is to provide a lift for heels which is readily detachable from the heel proper when the lift has become worn.

0 A further object of the invention is to so construct the heel that it may be readily attached and detached so as to render unnecessary the services of a person skilled in the art of shoe manufacturing and repairing to carry out the operation.

With the above and other objects in view, 5 reference is to be had to the accompanying drawings forming a part of this specification in which similar characters of reference indicate corresponding parts in all of the views, and in which—

0 Figure 1 is a fragmentary elevation of the rear portion of a shoe showing the improved heel in section, said section being taken on the line 1—1 of Fig. 2;

5 Fig. 2 is a horizontal sectional view taken on the line 2—2 of Fig. 1;

Fig. 3 is a detail disassembled view of the parts for securing the lift to the heel;

Fig. 4 is a detail sectional view of a modified form of the invention.

0 Referring more particularly to the drawings, the reference character 5 designates a shoe, and 6 designates the heel thereof. Secured to the outer face of the heel as by means of screws or the like 7, is a plate 8,

5 the screws 7 passing through holes 9 in said plate. The plate 8 has a straight edge 10, and on said straight edge is formed a T-head 11, the stem of the T being designated by the reference character 12.

0 The reference character 13 designates the heel lift and secured to said lift by means of

screws which pass through openings 14, is a plate 15. This plate 15 has a straight edge 16 on which are formed integral lugs 17 and each of said lugs is provided with perforations 18, the purpose of which will be hereinafter described. That end of the plate 15 opposite to the straight edge 16, is preferably rounded and said rounded edge is provided with a cut-out portion 19. Projecting 55 into the body of the plate on opposite sides of the cut out portion 19 thereof, are elongated slots 20, the distance between the ends of said slots being slightly greater than the length of the T-head 11 of the member 8. 60

The operation of the device is as follows: The lift 13 is turned in such position that the T-head 11 will enter the elongated slots 20. After the T-head 11 has been inserted in the elongated slots 20, the lift is turned 70 until the lugs 17 engage the breast thereof, as shown in Figs. 1 and 2. In some instances (depending upon the shape of the heel), it may be necessary to bend the lift relatively to the heel to permit of the lugs 17 positioning at the breast of the heel. With the parts in this position, screws 22 are passed through the openings 18 in the lugs 17, into engagement with the heel 6. When the lift 13 is attached to the heel, it 75 will be seen that withdrawal therefrom is prevented at the forward portion by the screws 22, and at the rear portion by means of the T-head 11 engaging beneath the side walls of the cut-out portion 19, as designated at 23, by dotted lines in Fig. 2. While in the present instance, the plates 8 and 15 are shown as secured to their respective parts, i. e., the heel and lift, it is apparent that they may be embedded in said parts instead of being secured thereto by screws, 80 without departing from the spirit of the invention.

In the form of the invention shown in Fig. 4, the plate 15 is embedded in the lift 95 13, said lift being provided with a recess 13' adapted to receive the T-head 11 of the plate 8.

Having thus described the invention, what is claimed as new is:

A heel for shoes comprising a body portion rigidly carried by the shoe and a de-

tachable tread portion, a slotted plate carried by the detachable tread portion, a plate carried by the rigid body portion of the heel, a T-head formed integral with said plate and right-angularly disposed with respect thereto, said T-head being adapted to be received within the slot of the first-

mentioned plate, and projecting tongues formed integral with said first-mentioned plate and perforated to receive fastening means whereby the said plate is secured to the breast of the rigid body portion of the heel. 10

ALBERT BRUNO SCHAEFER.
